METHOD OF FORMING BRAKE DRUMS

John MacLennan, Detroit, Mich., assignor to
 Kelsey-Hayes Wheel Company, Detroit, Mich.,
 a corporation of Delaware

Application March 26, 1934, Serial No. 717,497

1 Claim. (Cl. 29—152.2)

The invention relates to the manufacture of
 brake drums from sheet metal of uniform gauge
 and it is the object of the invention to obtain
 a product in which the braking flange is of
 5 greater thickness than the web portion of the
 drum. To this end the invention consists in the
 method as hereinafter set forth.

In the drawing:

Fig. 1 is a side elevation of the uniform gauge
 10 sheet metal blank from which the drum is to
 be formed;

Fig. 2 illustrates the first operation of reducing
 the thickness of the center portion of the
 blank relative to the thickness of the peripheral
 15 portion thereof;

Fig. 3 illustrates the bowing of the blank and

Fig. 4 the final operation of refashioning the
 bowed blank and forming the outwardly extending
 flange thereon.

20 The first step of my improved process is to
 cut a circular blank A from sheet metal of uniform
 gauge and of sufficient thickness to form
 the cylindrical brake flange. The mass of this
 blank corresponds to that of the finished product,
 25 but its diameter is initially less than that re-
 quired for forming the bowed blank. This blank
 A is then heated and subjected to a pressing op-
 eration between die members B and C. The
 die member C has its central portion C' project-
 30 ing beyond the peripheral portion C² and inter-
 mediate these two portions is the tapering por-
 tion C³. Thus when pressure is applied, the
 central portion of the blank A will be squeezed
 to reduce its thickness and to flow the metal
 35 radially outward into the space between the die
 B and the portion C² of the die C. This will in-
 crease the diameter of the blank and may also
 effect an upsetting operation which will increase
 the thickness of the peripheral portion.

40 After removal from the dies B and C, the
 blank is reheated and subjected to a bowing
 operation, being pressed by a plunger D into a
 female die E. The die E has the flaring mouth
 portion F in which the flat blank is first coned
 45 before entering the cylindrical portion E' and

this conical portion is preferably provided with
 annular grooves F' cut therein, leaving interme-
 diate portions F² of reduced area for fashioning
 the blank and thereby limiting the heat losses.
 The space between the parallel cylindrical sur- 5
 faces of the die D and cylindrical portion E' of
 the die E is greater than the thickness of the
 metal in the peripheral portion of the blank so
 that during bowing a slight clearance will be
 left between the blank and the plunger D to 10
 facilitate the easy withdrawal of the latter. The
 plunger D is provided with an enlarged portion
 D' which in conjunction with the die E forms an
 outwardly obliquely flaring flange as indicated
 at G. This is subsequently refashioned to form 15
 a reinforcing flange for the drum.

The next step in the operation is the refash-
 ioning of the bowed blank by pressing it be-
 tween dies H and I which suitably fashion the
 web portion. There are also annular dies J and 20
 K between which the oblique flange G is re-
 fashioned into the form indicated.

The drum constructed by the method above
 described has its web portion G' of a thin cross
 section in comparison with the cross section of 25
 the cylindrical flange G² and the outwardly ex-
 tends reinforcing flange G³. This increases
 the strength and diminishes the weight of the
 finished product.

What I claim as my invention is: 30
 In a method of forming blanks for brake
 drums, the step of hot-pressing a circular sheet
 metal blank of uniform gauge between dies hav-
 ing parallel faces, the face of one of said dies
 being in a plane and the other die having a cir-
 35 cular central portion less than the diameter of
 the blank in one plane, and a surrounding annu-
 lar portion in an outwardly offset plane and
 squeezing the metal of the blank in the central
 portion thereof outwardly and thereby thinning 40
 this portion and increasing the diameter of the
 surrounding portion and the thickness thereof
 within the limits imposed by the opposite faces
 of said dies.
